Application December 17, 1952, Serial No. 22,749

Term of patent 3½ years

(Cl. D81—10)

To all whom it may concern:

Be it known that we, Arthur I. Fader and Ira Nevin, both citizens of the United States, residing at Yonkers and the Bronx, New York, in the counties of Westchester and Bronx, and both in the State of New York, have invented a new, original, and ornamental Design for a Gas-Fired Broiler, of which the following is a specification, reference being had to the accompanying drawing, forming part thereof.

In the drawing:

Fig. 1 is a front perspective view of a gas-fired broiler, showing my new design;

Fig. 2 is a side elevational view of the same;

Fig. 3 is a top plan view of the gas-fired broiler; and

Fig. 4 is a rear elevational view of the same.

We claim:

The ornamental design for a gas-fired broiler, as shown.

ARTHUR I. FADER.
IRA NEVIN.
